UNITED STATES PATENT OFFICE.

EDWARD P. NOYES, OF WINCHESTER, MASSACHUSETTS, ASSIGNOR, BY MESNE ASSIGNMENTS, TO C. P. POWER COMPANY, OF NEWARK, NEW JERSEY, A CORPORATION OF NEW JERSEY.

ANTERIOR-THROTTLED CARBURETER.

993,097.

Specification of Letters Patent. Patented May 23, 1911.

Application filed May 6, 1908. Serial No. 431,088.

To all whom it may concern:

Be it known that I, EDWARD P. NOYES, a citizen of the United States, residing at Winchester, in the county of Middlesex and State of Massachusetts, have invented certain new and useful Improvements in Anterior-Throttled Carbureters, of which the following is a specification.

This invention relates to aspirating or liquid-fuel entraining carbureters such as are ordinarily placed on the suction side of an internal-combustion motor and operated by the passage of the air-current caused by the pumping action of the motor.

Heretofore it has been customary to throttle the mixture going to the engine by means of an externally-controlled valve located posterior to the mixing-chamber of the carbureter—that is, on the outlet side of said mixing chamber, between it and the engine—but such valves have certain disadvantages including a tendency to throw down or separate a portion of the aspirated fuel in liquid form, especially at low air-velocities, and inferior suction in the mixing chamber when the motor is performing slowly and the throttle partly closed, besides which they ordinarily have no provision for maintaining combustible proportions in the mixture when the air-supply to the mixing-chamber is below atmospheric pressure. The latter condition may exist when motor suction is applied to uses outside of the carbureting function, an example of such outside use being hereinafter described and claimed, and a further example being described and claimed in my Patent No. 979,788, dated December 27, 1910.

The object of my present invention is to avoid these disadvantages, and I accomplish the same by employing an anterior throttle—that is, one located on the air-inlet side of the mixing chamber—and controlling the air-supply which goes to the mixing-chamber, in place of the usual posterior throttle, together with suitable means for maintaining the air and fuel in combustible proportions at all degrees of mixing-chamber vacuum. In connection therewith I may provide an additional air-inlet, suitably controlled, whereby the motor suction can be applied to some outside purpose, such as lifting the fuel to supply the carbureter reservoir.

The accompanying drawing represents a

sectional diagrammatic view of a carbureter and fuel-supply apparatus embodying my invention and constructed on the open-jet or U-tube plan where the constant-level reservoir and jet-nozzle form two legs of a U.

1 is the air and mixture pipe having a mixing-chamber 2 with an outlet 3 leading to the motor and an air-inlet 4 controlled by a throttle valve 5 which has an operating lever 6 adapted to be connected with a governor or with a manual or similar operating device adjustable at will. This throttle-valve is thus located on the air-inlet side of the mixing chamber and constitutes the primary agent for controlling the motor by varying the density of an air-and-fuel charge, while its ingredients are maintained in combustible proportion. The form of the throttle-valve may be varied but it should preferably be a quick-acting device adjustable from its open to its closed position or vice versa by a relatively-short movement of the controlling connections, it being in this respect similar to an ordinary mixture throttle-valve.

7 is a float chamber or reservoir with float 8 and valve 9 and a suction-lift jet-nozzle 10 rising to an outlet in the mixing chamber 2, said jet-nozzle and the walls of the surrounding air-passage constituting a fuel-aspirating device adapted to be operated by motor suction, all in the usual form except that the float chamber is not normally under atmospheric pressure. I have omitted to show the needle-valve which is frequently employed to control the jet-nozzle, but this device, having either a normally-fixed adjustment or being automatically adjustable in any known or suitable manner may be employed in connection with my invention.

In order to keep the air and fuel in combustible proportions at all degrees of mixing-chamber vacuum it is desirable to employ in connection with the anterior throttle some means for maintaining a working preponderance of air-pressure in the float-chamber at all openings of the throttle-valve, and this pressure-difference between float-chamber and mixing-chamber should preferably remain substantially constant, though a slight departure from constancy will not destroy the combustibility of the mixture and may at times be desirable in order to meet the requirements of the motor. I contemplate various expedients within the

scope of the invention and have selected a preferred means for illustration as follows. Through a vacuum pipe or duct 11 connecting the top of the float chamber with a 5 chamber 19 immediately posterior to the throttle-valve 5, I establish, in the space above the fuel in said float chamber, the vacuum imposed by said valve (or it may be some derivative vacuum varying conformably with the throttle-imposed vacuum). To create a pressure down-drop between the chamber 19 and the mixing-chamber 2 I provide between said chambers an air-constricting device which, in the form here 10 shown, is a check valve 12 seated by a light spring 13 of adjustable tension. Any suitable equivalent for this device, not necessarily including an automatic moving part, may be employed. The spring check-valve 12 or its equivalent in combination with means such as the pipe 11 for transmitting the throttle-imposed vacuum to the rear surface of the fuel constitutes a means for maintaining the fuel and air in combustible 15 proportions throughout the range of the throttling device. If additional impulse on the fuel is desired in starting or at other times it may be had by opening a small valve 14 controlling an atmospheric air inlet-pipe 20 leading to the float chamber 7, or an additional impulse may be obtained by strengthening or tightening the spring 13, so as to create an increased pressure-difference 25 between float-chamber and mixing-chamber.

When throttle-valve 5 is partially closed the mixing-chamber has the benefit of a strong vacuum created by the engine suction, and not only does this increase the evaporative 30 tendency of the fuel by removing air pressure from its surface, but it also makes available a stronger impelling force on the fuel than is attained with posterior-throttled carbureters. As the throttle-valve does not 35 obstruct the mixture-passage there is no resulting tendency to mechanically separate a portion of the fuel from the air after leaving the mixing-chamber.

This invention, furthermore, enables me to 40 employ the engine vacuum for extraneous purposes. It may be used for example to lift the fuel through a pipe 16 from a suitable source of supply into an elevated tank 17. The latter can be sealed air-tight and 45 connected by a pipe 18 with the vacuum pipe 11 and the chamber 19 posterior to throttle 5. When valve 20 in pipe 16 and valve 21 in pipe 18 are opened the engine suction will 50 cause atmospheric pressure at the main store 55 of fuel supply to force the fuel up into tank 17. When the latter is full, as evidenced by a gage 22, valve 20 is closed. Fuel descends by gravity from tank 17 into float chamber 7 through a pipe 23 past float valve 9. 60 When employing a float valve in the reser-

voir 7, I may embody the tank 17 as a permanent feature of the fuel supply system for the carbureter and leave the valve 21 open. The partial vacuum in tank 17, which is the same as that in float chamber 7, then avoids 65 an excessive pressure tending to force fuel past the float valve 9. I may however employ any suitable constant-level device in place of the float valve and retain the tank 70 17 in connection therewith. Tank 17 may 75 be the main fuel tank in the supply system for the carbureter or it may be a local tank periodically filled. Variations of this illustrated arrangement are obviously permitted. For example, since I have made available 80 the difference between atmospheric pressure and motor-vacuum pressure as an agency for lifting the fuel to the carbureter, it would be possible to altogether omit a gravity-feed 85 of fuel, or a super-atmospheric pressure feed such as is sometimes employed, and connect the carbureter supply pipe directly to any suitable supply tank at a lower level than the carbureter, though not so low as to exceed the lifting power of said pressure-difference. The equivalent of such arrangement would be realized by leaving valve 20 90 permanently open and shutting valve 21, valve 25 being also closed.

24 is a pipe connected with chamber 19 95 and containing a stop-valve 26 whereby the engine vacuum may when desired be applied to other outside purposes. In my Patent No. 979,788, aforesaid is illustrated the use of explosive-engine vacuum for dust-collection, and my present carbureter and fuel-supply system can be employed in connection with the apparatus there shown or other vacuum-using apparatus.

It will be understood however that the 100 carbureter is not exclusively confined to operation at air-pressure from and below the atmospheric, since its principle of construction makes it independent of the pressure-level of the air-supply, which is not true of the ordinary carbureter with a float-chamber open to the atmosphere.

I do not herein claim broadly the combination in a liquid fuel carbureter adapted 105 to be operated by motor suction, of a throttle-valve controlling the air current at a point anterior to the mixing point, and means adjustable at will for maintaining a working preponderance of air pressure in 110 the fuel reservoir at all degrees of mixing-chamber vacuum, as this subject-matter is described and claimed in my earlier application, Serial No. 324,004, filed June 29, 1906, my present carbureter being a specific form 115 of the invention thus designated.

I claim:

1. In a liquid-fuel carbureter, the combination of a mixing-chamber having an air-inlet passage, a throttle-valve controlling 120 said passage, a constant-level fuel-reservoir 125 130

having an outlet to said mixing-chamber of normally-constant aperture, and means for maintaining a substantially-constant difference of air-pressure between said fuel reservoir and mixing-chamber throughout the operation of the carbureter.

2. In a liquid-fuel carbureter, the combination of a mixing-chamber having an air-inlet passage, a throttle-valve adjustable to open and close said passage, a spring-seated check-valve in the air-passage between the throttle valve and the mixing-chamber, a fuel-reservoir having a fuel-outlet to said mixing-chamber, and a vacuum duct connecting the upper part of said fuel-reservoir with the air-inlet passage at a point between the throttle-valve and the check-valve.

3. In a liquid-fuel carbureter, the combination of a mixing-chamber having an air-inlet passage, a throttle-valve adjustable to open and close said passage, a spring-seated check-valve in the air-passage between the throttle valve and the mixing-chamber, a fuel-reservoir having a fuel-outlet to said mixing-chamber, a vacuum duct connecting said fuel-reservoir with the air-inlet passage between the throttle-valve and the check-valve, and a valve-controlled atmospheric air inlet to said reservoir.

4. In a vapor carbureter operated by motor suction, the combination of means to supply liquid fuel, means for aspirating the fuel by the passage of the suction air-current, two air-inlet passages for supplying air to the aspirating means, a throttle-valve in one of the air-inlet passages, an adjustable stop-valve in the other air-inlet passage, and means for maintaining the air and fuel in combustible proportions throughout the range of said valves.

5. A liquid-fuel carbureter comprising air-and-fuel mixing means, throttling means for controlling the air-supply anterior to the mixing point, a constant-level reservoir for supplying fuel to the mixing means, means for causing the air-pressure in said reservoir

to vary conformably with the throttled air-pressure, and means for applying the vacuum imposed by said throttle-valve to supply fuel to said reservoir from a lower level. 50

6. A liquid-fuel carbureter comprising a mixing-chamber having an air-inlet passage, a throttle-valve adjustable to open and close said passage, a constant-level fuel reservoir having a fuel-outlet to said mixing-chamber, means to maintain a working preponderance of air-pressure in said reservoir at all degrees of mixing-chamber vacuum, a branch conduit entering the air-inlet passage at a point between the throttle-valve and the 60 mixing-chamber for applying the carbureter vacuum to an outside purpose, and a stop-valve controlling said branch conduit.

7. A carbureter comprising a mixing-chamber, a fuel-reservoir having a jet-nozzle 65 rising to an outlet in said chamber, a float-valve to maintain a constant level in said reservoir, an elevated sealed tank having a gravity feed to said reservoir past the float-valve and provided with a suction-lift fuel-inlet pipe, a stop-valve in said pipe, an anterior air-throttle controlling the vacuum in said mixing-chamber, means to establish the throttle vacuum in said reservoir, and means to establish the throttle vacuum at will in 75 said tank.

8. A motor carbureting and fuel-lifting system comprising a suction-operated fuel-aspirating carbureter, means for controlling the mixture density by throttling the air-supply of said carbureter at a point anterior to the mixing point, and means for lifting the fuel from a source of supply to or above the level of the carbureter by the pressure-difference due to the motor vacuum. 80

In testimony whereof I have hereunto set my hand in the presence of two subscribing witnesses, the 4th day of May, 1908.

EDWARD P. NOYES.
